SHEET METAL WAINSCOTTING FOR BATHTUB ENCLOSURES OR THE LIKE

Isaac F. McBride, P.O. Box 681, Boise, Idaho

Filed Aug. 23, 1963, Ser. No. 304,074

3 Claims. (Cl. 52—35)

This invention relates to sheet metal wainscoting for bathtub enclosures or similar spaces, and has as its primary object the provision of a wainscoting comprised of single sheets of steel or other desired metal about the three enclosed sides of a bathtub enclosure to obviate the necessity of the use of tile or other similar material and the grouting customarily employed with such tile.

A further object of the invention is the provision of such a wainscoting, together with improved means for holding the sheets of metal in juxtaposition to the walls, as well as means whereby a single sheet of metal may be inserted in the rear of the enclosure by manipulation without the necessity for the use of screws or similar fastening devices.

A still further object of the invention is the provision of a structure of this nature whereby the necessity for replacement of tiling, when loosened or cracked by the settling of the building structure, or other similar occurrences, is obviated.

Still another object of the invention is the provision of such a wainscoting wherein the corners will be made water tight without the necessity of caulking or other sealing.

A further object of the invention is the provision of a device of this character provided with trim beads around the top and end edges thereof, wherein the sheets of metal wainscoting are securely held in position within the beads.

Still another object of the invention is the provision of such wainscoting wherein the sheets of metal may be glazed for ornamental purposes in a wide variety of colors with the beads in contrasting or matching colors as desired, and wherein any suitable ornamentation or decoration may be readily applied to the sheet metal.

A further object of the invention is the provision of wainscoting of this character which may be readily applied to a wide variety of sizes and shapes of bathtub enclosures.

Still other objects reside in the combinations of elements, arrangements of parts, and features of construction, all as will be more fully pointed out hereinafter and disclosed in the accompanying drawing wherein:

FIGURE 1 is a perspective view, parts thereof being shown in section, of a bathtub enclosure provided with wainscoting in accordance with the instant invention.

FIG. 2 is an enlarged sectional view, partially broken away, taken substantially along the line 2—2 of FIG. 1 as viewed in the direction indicated by the arrows.

FIG. 3 is an enlarged sectional view, partially broken away, taken substantially along the line 3—3 of FIG. 1 as viewed in the direction indicated by the arrows.

FIG. 4 is an enlarged fragmentary detail perspective view of one of the corners of the wainscoting, and

FIG. 5 is an enlarged detail sectional view showing a modified form of the invention wherein a center strip is provided for two sheets in end-to-end relation.

Similar reference characters refer to similar parts throughout the several views of the drawing.

Having reference now to the drawings, and more particularly to FIG. 1, there is shown at 10 a bathtub of any desired conventional type which is set in a bathtub enclosure which is comprised of front and rear end walls 11 and 12 respectively, and a back or rear wall 13, the tub being sized to fit conveniently within the recess formed by the walls 11, 12 and 13. The wainscoting

2

or enclosure for the tub is comprised of a first end sheet 14 which is suitably apertured to provide for the extension of control handles 15' therethrough and an opposed substantially identical end sheet 15. The end sheets 14 and 15 are provided with right angularly disposed flanges 16 and 17 respectively. Secured to rear wall 13 adjacent to each flange 16 and 17, respectively, is a strip 18 and 19 respectively which extends parallel to its adjacent flange but is spaced therefrom by spacers 18' and 19' to provide channels 20 and 21 respectively. The strips are wider than their associated flanges and are provided in the extending edges thereof with screw holes 22 for the reception of securing screws 23. Strips 18 and 19 are adapted, when the sheets 14 and 15 are in position, to abut rear wall 13.

The channels 20 and 21 include rear walls 24 and 25 respectively and confronting open ends 26 and 27. The channels are adapted to receive the opposite ends of a rear sheet 30, the rear sheet being carefully cut to be of a width in excess of the distance between the confronting open ends 26 and 27 of the channels but less than the distance between the rear end 24 or 25 and the opposite open end 27 or 26 respectively, thereof. By virtue of this arrangement one end 31 of rear wall 30 may be slipped into the channel 21, for example, until the opposite edge 32 of sheet 30 is inward relative to the open end 26 of the opposite channel. The end 32 is then aligned with the opposite channel and the entire sheet moved to the right, as viewed in FIG. 1 so that the ends 30 of strips 18 and 19 cover the edges 31 and 32. At this time the sheet 30 is completely prevented from disengagement except by a reverse procedure analogous to that just described.

It is to be noted that by this arrangement the heads 35 of screws 23 extending through flanges 16 and 17 are completely concealed.

The outer or free edges of end sheets 14 and 15 are protected by beads 35, which are substantially identical but opposite, and which comprise generally channel-shaped members which include rear spring clips 36 which hold the beads to the exposed edges. Screw holes 37 may accommodate holding screws 23 identical to the previously described screws, with the heads of the screws being covered by the outer wall of the bead.

Identical beads 40 provided with substantially identical internal spring clips 41 are positioned over the tops of the end and rear panels, with the extremities 42 of rear bead 40 being widened, if desired, to overlie the tops of the flanges 16 and 17. If screws are employed to hold rear panel 30 in position, they may be extended through that portion of the top of the sheet covered by the bead 40.

The lower portion of each sheet is adapted to seat in a channel 45 which is positioned on the edge of the tub 10 immediately adjacent the rim 46 thereof which is normally embedded in the adjacent wall, and the channel tightly caulked as at 47 to the top of the margin of the tub 10. The length of channel 45 is such that the ends thereof terminate short of the opposed edges of flanges 16 and 17 and strips 18 and 19.

The sheets 14, 15 and 30 may be made of any desired material, although sheet metal such as sheet steel or sheet aluminum has been found preferable. Obviously, waterproof plastic may be employed if desired. The sheets may be glazed in any desired color or combination of colors, or may be marked in simulation of varicolored tiles, and the beads 35 and 40 may be correspondingly or contrastingly colored as desired to provide a highly ornamental effect.

In FIG. 5 a slightly modified form of construction is disclosed wherein rear sheet 30 is comprised of two portions 30a and 30b, and a central strip generally indicated at 50 is extended vertically down the center of the rear

wall 13. The strip 50 includes a plate-like portion 51 and a central vertical strip 52 on opposite sides of which extend the margins of a flange plate 53 to provide oppositely disposed channels 54 and 55 into which the ends 32a and 32b of the opposed portions may be inserted, with the opposite edges of the portions extending respectively into the channels 21 and 20, the method of insertion being identical to that previously described. In this modification of the invention the edges of the plate 51 extend beyond the ends of the flanges 53 and may be provided with openings 56 for the reception of additional securing screws 23, the screw heads being completely concealed by the edges of the portions 30a and 30b when the parts are in related assembly.

From the foregoing it will now be seen that there is herein provided an improved wainscoting for bathtub enclosures which accomplishes all of the objects of this invention and others including many advantages of great practical utility.

As many embodiments may be made of this inventive concept, and as many modifications may be made of the embodiment hereinbefore shown and described, it is to be understood that all matter herein is to be interpreted merely as illustrative, and not in a limiting sense.

I claim:

1. Sheet wainscoting for a bathtub enclosure including a rear wall and opposite end walls, and enclosing a bathtub having one side in abutting relation with said rear wall and its opposite ends each abutting one end wall, including a generally U-shaped horizontal channel extending along the top of the side of the bathtub abutting said rear wall, vertically extending strips secured to the rear wall each having its outside edge in abutting

5
10

relation with the adjacent end wall, vertical spacers carried by each strip adjacent its associated end wall, end sheets covering a substantial portion of each end wall and each having a substantially perpendicular flange at its end adjacent said rear wall, each flange abutting a spacer, and being of a width greater than the spacer, but less than that of the adjacent strip, each said strip and its adjacent flange defining a vertical channel having one end closed by a spacer, the other end being open with the open ends in confronting relation, and a rear sheet of a width greater than the distance between the confronting open ends of said channel but less than the distance between the closed ends of said vertical channels.

2. The structure of claim 1 wherein screw holes are provided in the edges of said strips extending beyond said flanges and screws are extended into the adjacent wall to secure said strips thereto, the subsequent insertion of said rear wall behind said flanges covering the screw heads.

3. The structure of claim 1 wherein beads are secured along the outer edges of said end walls and additional beads are secured along the top edges of said end and rear walls.
